UNITED STATES PATENT OFFICE

165,769

TEXTILE FABRIC

Ben Leerer, New York, N. Y.

Application March 8, 1951, Serial No. 14,429

Term of patent 3½ years

(Cl. D92—1)

To all whom it may concern:

Be it known that I, Ben Leerer, a citizen of the United States of America, residing in New York, county of New York, and State of New York, have invented a new, original, and ornamental Design for a Textile Fabric, of which the following is a specification, reference being had to the accompanying drawing, forming part thereof,

Fig. 1 is a plan view of a textile fabric, showing my new design.

Fig. 2 is approximately one-half of the design unit on a larger scale.

The design unit is outlined by broken lines and is repeated over the surface of the textile fabric as indicated.

I claim:

The ornamental design for a textile fabric, substantially as shown and described.

BEN LEERER.
